UNITED STATES PATENT OFFICE

152,250

DESIGN FOR A GLASS PLATE FOR LIGHTING FIXTURES

Kurt Franck and Vearl Wince, Newark, Ohio, assignors to Holophane Company, Inc., New York, N. Y., a corporation of Delaware

Application March 21, 1946, Serial No. 127,749

Term of patent 14 years

(Cl. D48—16)

To all whom it may concern:

Be it known that we, Kurt Franck and Vearl Wince, citizens of the United States of America, both residents of Newark, in the county of Licking and State of Ohio, have jointly invented a new, original, and ornamental Design for Glass Plate for Lighting Fixtures, of which the following is a specification, reference being had to the accompanying drawing, forming a part thereof.

In the drawing:

Figure 1 is an end elevational view of the glass plate for lighting fixtures, showing my new design; and

Figure 2 is an inverted plan view of the same.

The characteristic feature of our design resides in the flutes on the upper concave surface and the

refracting ribs on the other surface on a glass plate of the shape shown.

We claim:

The ornamental design for a glass plate for lighting fixtures, as shown and described.

KURT FRANCK.
VEARL WINCE.
